W. DE GOEY

VANITY CONTAINER

Filed March 19, 1925

Fig. 1.

Inventor

William De Goey

By

Koratis E. Bellows

Attorney

UNITED STATES PATENT OFFICE.

WILLIAM DE GOEY, OF PROVIDENCE, RHODE ISLAND.

VANITY CONTAINER.

Application filed March 19, 1925. Serial No. 16,643.

To all whom it may concern:

Be it known that I, WILLIAM DE GOEY, a citizen of the United States, residing at Providence, in the county of Providence and State of Rhode Island, have invented certain new and useful Improvements in Vanity Containers, of which the following is a specification.

My invention relates to vanity containers of the vessel type, and has for its essential objects adaptability for use upon the dresser, bureau, or other article of furniture, in distinction from portable use; to adapt a container of this type to use for both powder and rouge; to disguise such double use and preserve unbroken the external contour of the vessel; and to attain these ends in a structure inexpensive to construct and convenient to operate.

20 To the above ends essentially my invention consists in such parts and in such combinations of parts as fall within the scope of the appended claims.

In the accompanying drawings which 25 form a part of this specification,

Figure 1 is a top plan view of my container, and

Figure 2, a side elevation, partly in transverse central section, of the same.

30 Like reference characters indicate like parts throughout the views.

In detail my container consists of a body 4 composed of glass, china, or other suitable material, having a circular contour, and 35 comprising a flat bottom 5, a swelled side 6, a substantially flat top 7, centrally of which is an opening 8 bounded by a vertical flange or rim 9. The body has greater horizontal than vertical dimensions, and in this instance is substantially elliptical in cross section. For these reasons the body is not readily accidentally tipped over.

A hollow cover 11 of metal, china, glass or other material is fitted to the body 4. In 45 detail the cover comprises a circular convex top 12 having a swelled projecting side 13 and a depending flange 15, around an opening 16 in its bottom 17. This flange has a beaded bottom 18 and is a sliding fit upon the flange or rim 9, and the bottom of the former rests on the top 7 of the vessel body 4. The top of the cover has a circular open-

ing 20 which forms the mouth of a receptacle pocket 21. The pocket is cylindrical in shape, having a bottom 22 and a side wall 55 23 provided with an internal annular shoulder 24 at its top, to afford a rest for a convex closure disk 25 which closes the pocket. The disk is thus flush with the top 12 of the cover 11. Integral with the center of the 60 disk, and spun up therefrom is a hollow knob member 26 comprising a tapering body portion 27 and a convex lid 28 connected to the body by a hinge 29. The body has an internal annular shoulder 30. 65

The pocket or receptacle 21 is adapted to receive a powder or other compact 32, and is wholly concealed from view from the exterior of the cover 11. Loose powder or other cosmetic 33 may be carried in the vessel body 4. The pocket is accessible by lifting the member 25, and the body 4 is accessible by manually lifting the member 11. The receptacle formed by the knob member is adapted to receive and support on the 70 shoulder 30 a rouge or other compact 35 which is accessible by lifting the lid. 75

I claim:

1. In a vanity container, a transversely elliptical vessel provided with a central 80 opening, a vertical rim upon the vessel around the opening, a cover comprising a hollow body provided with an opening in its top, a pocket fast to the top around the second opening and depending into the 85 body, said pocket being provided in its top with an internal annular shoulder, a detached closure disk seated on the shoulder and flush with the top of the body, and a flange on the cover slidably engaging the 90 rim.

2. In a vanity container, a vessel, a cover on the vessel provided with a central receptacle, a plate in the cover constituting a closure for the receptacle, and a hollow knob 95 member centrally disposed on the plate comprising a flaring body portion provided with an internal annular seat adapted to support a compact and a lid hingedly connected to the body portion. 100

In testimony whereof I have affixed my signature.

WILLIAM DE GOEY.
